UNITED STATES PATENT OFFICE.

CHESTER J. SMITH AND CHARLES ERNEST BALDWIN, OF JAMESTOWN, NEW YORK.

MEASURING-MACHINE.

1,204,511.

Specification of Letters Patent. Patented Nov. 14, 1916.

Application filed October 13, 1915. Serial No. 55,622.

To all whom it may concern:

Be it known that we, CHESTER J. SMITH and CHARLES ERNEST BALDWIN, citizens of the United States, residing at the city of 5 Jamestown, in the county of Chautauqua and State of New York, have invented certain new and useful Improvements in Measuring-Machines, of which the following, taken in connection with the accompanying drawings, is a specification.

The invention relates to measuring machines for cloth or any material which may be drawn through said machine so as to indicate the measurement on the registering 15 mechanism of said machine; and the invention consists in providing a simple measuring machine which may be attached to the edge of a table or counter for manually drawing the material to be measured there- 20 through and providing registering mechanism which gives the exact measurement; and second, to provide a cutting mechanism for cutting narrow material and for notching the edge of wide material at the end of 25 the measurement; and third, to provide mechanism for returning the registering mechanism to the normal or zero position ready to begin a new measurement; and the invention consists in the novel features 30 and combinations hereinafter set forth and claimed.

In the drawings, Figure 1 is a perspective view of the measuring machine attached to the edge of a table or counter. Fig. 2 is a 35 perspective view of the mechanism with the casing removed showing the registering disks or wheels, the cutting knife and the operating mechanism. Fig. 3 is a sectional view at line X³ X³ in Fig. 1 showing a side 40 elevation of the machine as attached to the edge of a table or counter, with the operating rollers in normal position. Fig. 4 is an elevation of the inner side of the disk which registers the inches or minor measurements 45 and the mechanism for returning the registering disks to zero, also showing the knife and other parts. Fig. 5 is a sectional view at line Y⁵ Y⁵ in Fig. 4, showing the two 50 registering disks and the end of the lever for returning said disks to zero and the supporting frame; and Fig. 6 is a perspective view of the inner end of said lever. Fig. 7 is a perspective view of the inner side of the

disk for registering the yard or major measurements.

Like numerals of reference refer to corresponding parts in the several views.

The numeral 10 designates the sheet metal casing which has the openings 11 and 12 for observing the numerals on the registering disks. The sheet metal casing 10 is supported upon a frame consisting of the rods and plate 28 and the cast plate 13, which cast plate extends out at right angles in the shelf 14 and in the projecting lug 15 65 a spaced distance from the shelf 14 through which lug the thumb-screw 16 operates to clamp the machine on the edge of the table or counter between said screw 16 and the shelf 14. The plate 13 has the standard 70 thereon to revolubly support the arbor of the operating or measuring roller 18 and gear 19.

The shelf 14 has the flange 20 and slot 22 near one end. A notching or cutting knife 75 21 is pivotally attached to the plate 13 near the inner end of said knife 21 to cut downwardly with a shearing cut against the flange 20 alongside the slot 22, a spring 23 being attached to the inner end of the knife 80 21 to return said knife to its normal raised position ready for another cut. It is apparent that the knife 21 might be extended to make a longer cut than the one shown, but the preferred purpose of the knife 21 85 is to cut narrow material and to start the cut on wide material at the end of the measurement, since the severing of wide fabrics is more easily and quickly accomplished by tearing or with a pair of shears or scissors 90 and a long knife would be unwieldy and cumbersome.

A roller 24 is held by a supporting plate 25 and a spring 42 firmly against the under- 95 side of the roller 18 to press the fabric against said roller 18 and insure the accurate movement of said measuring roller 18 when the material is drawn between the two rollers. The roller 24 is preferably mounted in the shelf 14, which is constructed with an outer frame and a slotted plate fitting onto said outer frame, thereby forming a central opening within which said roller 24 and the plate 25 are mounted, the roller 24 moving up and down through 100 105 said slot.

The registering disks 26 and 27 are revolvably supported upon the frame 28 attached to the plate 13, a shaft 43 being supported upon the plates 28 and 13 for revolvably supporting the registering disks 26 and 27. The registering disk 26 which registers the minor measurements is operated by the measuring roller 18 by means of the gears 19 and 29, gear 29 being 5 revolvably mounted on the supporting shaft 43 and pressed against the registering disk 26 so as to normally revolvably move in unison therewith, and so that when the roller 18 is revolved by drawing the material to be measured between the rollers 18 and 24, the registering disk 26 will be revolvably moved also by means of the connective gears 19 and 29.

The second or major registering disk 27 20 has the internal gear 30 thereon within which a gear 31 meshes. The gear 31 is mounted on a revolvable arbor in a lever 32, (within) and between the disks 26 and 27 which arbor has an operating star-shaped 25 or toothed wheel 33 on the opposite end thereof. A pin 34 is provided on the inner side of the disk 26 in the path of the toothed wheel 33 so as to move said toothed wheel a step at a time, which step corresponds to 30 the yard measurements on the periphery of the registering disk 27. In order to hold the toothed wheel 33 and gear 31 from moving inaccurately, a roller 35 is provided which is pressed between the teeth of the 35 wheel 33 by means of the leaf spring 36 which is supported upon the lever 32. The roller 35 permits the turning of the wheel 33 a tooth at a time but stops said wheel 33 and holds the yard registering disk 27 accurately and firmly in position.

It is now obvious that the drawing of the material to be measured through between the rollers 18 and 24 will rotatably and accurately move the registering disk 26 and 45 that each revolution of said disk 26 accurately moves the registering disk 27, one step thereby registering the length of the material that is drawn through between said rollers 18 and 24.

50 In order to return the registering disks 26 and 27 to their normal position or zero, a pair of heart-shaped cams 37 and 38 are provided, the cam 37 on the inner side of the disk 26 and the cam 38 on the inner side 55 of the disk 27. A pair of rollers 39 are mounted on a crosswise pin 40 on opposite sides of the inner end of the lever 32 to engage the cams 37 and 38 when the inner end of said lever 32 is moved upwardly. 60 The lever 32 is pivotally supported on a stud on the plate 13 at 41 so that manual pressure on the outer end of the lever 32 will throw the inner end upward thereby bringing the rollers 39 into contact with the cams 65 37 and 38, and the peculiar shape of said

cams with the pivotal position of the lever 32 causes said rollers 39 to move toward the center of the disks 26 and 27 thereby simultaneously and quickly moving said disks back to their normal position when the lever 32 is pressed downwardly.

In order to insert the cloth or material to be measured between the rollers 18 and 24, the roller 24 is moved away from the roller 18 by means of an arm 44 which is attached to the end of the shaft 45 upon which the plate 25, which supports the roller 24, is firmly attached. An arm 46 is attached to the lever 32 and extends beneath the arm 44 so that whenever the lever 32 is depressed the arm 46 presses the arm 44 to one side thereby turning the shaft 45 and moving the roller 24 downward, as shown in dotted line in Fig. 3, and thereby permitting the easy insertion of the material to be measured. The 85 spring 42 is attached to the arm 44 or to the set-screw for said arm and to one of the rods of the frame 28 thereby always drawing the parts back to normal so that the roller 24 presses firmly against the roller 18.

An adjusting screw 47 is provided on the frame 28 in line with the lever 32 against which said lever 32 strikes when it is returned to the normal position by means of the spring 48, which spring is attached to the frame 28 at one end and to a hook on the underside of the lever 32. The hook is placed between the pivotal point 41 and the registering disks 26 and 27 in order to draw downward on the inner end of the 100 lever 32 and upward on the outer end. This brings a spring pressure upon gear 31 so that it is normally held in mesh in the gear 30 and the screw 47 regulates the depth of mesh of these two gears, otherwise the 105 spring 48 would draw said gears too heavily into mesh and thereby stop the movement of the registering disk 27.

It is apparent that when the disks 26 and 27 are returned to the normal or zero position, the gear 31 must be raised out of mesh with the gear 30 so as to leave the disk 27 free to rotate back to said zero position. This is also accomplished by the depression of the lever 32 which raises the gear 31 out 110 of mesh with the gear 30 and permits the rollers 39 to engage the cams 37 and 38.

Whenever the lever 32 is depressed it is apparent that the arm 46 engages the arm 44 and depresses the roller 24, thereby releasing the material to be measured and the operating roller 18, thereby permitting all the parts to rotate freely in returning the registering disks to their zero position. A spring 50 is provided on the frame 28 which bears against the side of the disk 27, entering a depression 49 in the side of said disk which depression is made in the side of said disk at the point which holds the disk 27 at said zero position. The spring 50 125 130

slides easily along the rotating disk while it is returning to normal but when the rollers 39, enter the groove at the top of the heart-shaped cams 37 and 38 and stop there the 5 spring 50 enters the groove or depression 49 thereby holding the registering disk 27 firmly in the zero position. The disk 26 is held in the zero position by the pressure of the gear 29. When it is desired to measure 10 an entire piece of material, it is started from the line 51 on shelf 14 opposite the centers of the operating rollers 18 and 24, the registering disks 26 and 27 having first returned to the zero position by the depression 15 of the lever 32. The piece of material may then be inserted while the lever 32 is depressed and with the release of the lever 32 the material is clamped firmly between the two rollers 18 and 24 and may be drawn 20 through from end to end thereby registering on the disks 26 and 27 the exact length of said piece of material. When it is desired to cut a certain portion from a piece of material, the end of the material is placed against 25 the cutting flange 20 as it is inserted between the rollers 18 and 24 and is drawn through until the desired amount is registered on the disks 26 and 27 at which point the knife 21 is depressed thereby cutting or notching 30 the edge of the material at the end of the measurement. The lever 32 is depressed to release the material thereby simultaneously removing the gear 31 out of mesh with the gear 30 so as not to disturb the disk 27 35 until it is moved by the roller 39 engaging the cam 38. The depression of the lever 32 also simultaneously depresses the roller 24 and as the two rollers 39 move upward, the lever 32 returns the two registering disks 40 26 and 27 to the zero position, and upon its release leaves the parts in normal position ready for a new measurement.

The numerals on the registering disks 26 and 27 are preferably made so as to be read 45 from the opposite side from that of which the operating rollers 18 and 24 are placed. This arrangement brings the right hand of the operator into position for operating the lever 32 and drawing the material through 50 the machine.

We claim as new:

1. A measuring machine comprising a frame, rollers revolubly mounted on said frame to be actuated by drawing the material to be measured therebetween, registering disks rotatively mounted on said frame, a lever pivotally mounted on said frame and extending between said registering disks, geared connection between one of 55 said rollers and one of said disks to rotatively move the same, mechanism on said lever to rotatively move the other registering disk one step when said lever is in normal position by each complete rotation of 60 the first registering disk, said registering

disks being released from said mechanism when said lever is moved from normal position.

2. A measuring machine comprising a frame, operating rollers revolubly mounted 70 on said frame to be actuated by drawing the material to be measured therebetween, registering mechanism connected to said operating rollers to register the measurement, one of said rollers mounted on a 75 spring arm to normally press said roller against the other roller, and a lever to simultaneously move said spring pressed roller away from the other roller to permit the insertion of the material to be measured 80 between said rollers, and turn said registering mechanism back to zero.

3. A measuring machine comprising a frame, operating rollers revolubly mounted on said frame to be actuated by drawing the 85 material to be measured therebetween, registering mechanism actuated by said operating rollers to register the measurement, a lever and mechanism thereon to return said registering mechanism to the zero position, 90 one of said operating rollers being operatively connected to said lever so that said roller will be moved away from the other roller when said lever returns said registering mechanism to the zero position. 95

4. A measuring machine comprising a frame, operating rollers rotatively mounted on said frame to be actuated by drawing the material to be measured therebetween, a registering disk having measuring indications thereon, connective gearing between the shaft of one of said rollers and said registering disk to rotatively move the same, a second registering disk facing the first registering disk having an internal gear therein, a lever extending between said registering disks, a gear revolubly mounted on an arbor on said lever and meshing in said internal gear, a star wheel on the opposite end of said arbor to turn the same, and a pin on said first registering disk to engage said star wheel and turn said second registering disk one step at a time. 105 110

5. A measuring machine comprising operating rollers to be actuated by drawing the material to be measured therebetween, a registering disk having measuring indications thereon, connective gearing between the shaft of one of said rollers and said registering disk to operate the same, a second registering disk facing the first registering disk having an internal gear therein, a lever extending between said disks, a gear revolubly mounted on said lever and meshing in said internal gear, a star wheel 115 mounted on the same shaft as said gear on said lever to turn therewith, a pin on said first registering disk to engage said star wheel and turn said second registering disk 120 one step, and mechanism operably connect- 125 130

ed to said lever to separate said operating rollers for the insertion of the material to be measured.

6. A measuring machine comprising operating rollers to be actuated by drawing the material to be measured therebetween, a registering disk having measuring indications thereon, connective gearing between the shaft of one of said rollers and, said 5 registering disk to rotate the same, a second registering disk facing the first registering disk having an internal gear therein, a lever extending between said gears, a gear revolv-
10 bly mounted on said lever and meshing in
15 said internal gear, a star wheel mounted

on the same shaft as said gear on said lever to turn therewith, a pin on said first registering disk to engage said star wheel and turn the same and said second registering disk one step, and mechanism on said lever 20 and registering disks for returning said registering disks to the zero position.

In testimony whereof we have affixed our signatures in the presence of two witnesses.

CHESTER J. SMITH.
